UNITED STATES PATENT OFFICE.

JAMES S. BROWER, OF ST. LOUIS, MISSOURI.

INCUBATOR.

1,401,756.

Specification of Letters Patent. Patented Dec. 27, 1921.

Application filed November 13, 1920. Serial No. 423,779.

To all whom it may concern:

Be it known that I, JAMES S. BROWER, a citizen of the United States, residing at city of St. Louis, State of Missouri, have invented a certain new and useful Improvement in Incubators, of which the following is a full, clear, and exact description, such as will enable others skilled in the art to which it appertains to make and use the same, reference being had to the accompanying drawings, forming part of this specification, in which—

Figure 1 is a perspective view of my improved incubator.

Fig. 2 is a rear side elevational view of the same.

Fig. 3 is an enlarged cross sectional view showing the controlling mechanism for the hot water and ventilator.

Fig. 4 is a detail view of the hot water controlling valve.

Fig. 5 is a detail sectional view, illustrating the connection between the thermostat and the balanced lever.

This invention relates to a new and useful improvement in incubators, the object being to provide improved mechanism for controlling the supply of the hot water to and the ventilation of the incubating chamber, whereby the regulation of the temperature in the chamber is under sensitive control enabling the chamber temperature to be maintained at the desired degree of heat and within a range of a fraction of one degree.

In the drawings, 1 indicates a unit of an incubator which can be extended by other units as indicated at 1^a, in Fig. 1, thus forming a battery, each unit being supplied with hot water from a common heater indicated at 2 and each unit having its individual hot water and ventilator regulating mechanism so that the temperature in one unit will not affect or modify the temperature of another. 3 indicates a hot water supply pipe leading from the top of the hot water system of the heater 2 and into an expansion tank 4 provided with a water gage 5, for well understood purposes. 6 indicates the hot water supply pipe for the incubating units provided at intervals opposite or behind each unit with standpipes 7, the upper ends of which standpipes terminate in a T-coupling 8 and having its inner upper edge beveled or ground to form a valve seat 7^a.

9 indicates the coil pipe extending into the upper portion of the incubating chamber,

thence around said chamber and out into a connecting pipe 10 in which latter is located a check valve 11. Pipe 10 connects with a T-coupling 12 from the upper leg of which extends an open ended pipe 13 while from the lower leg leads a connecting pipe 14 into a return pipe 15 communicating with the lower portion of the hot water system in the heater 2.

The pipes 6 and 15 may extend behind the battery of incubating units, the size of the water heater and said pipes of course depending upon the number of incubating units in the battery which are to be heated. 16 indicates a standpipe extending from the T-coupling 8, said standpipe being of slightly larger diameter than the pipe 7 so that the ball valve 17 may pass therethrough from above, to coöperate with the valve seat 7^a.

18 indicates a chain by which the ball valve is suspended, said chain being connected by a suitable hook 19 to one end of a bent lever 20. Lever 20 is carried by a plate 20^a 80 the latter being fulcrumed in the upper end of a block 21, projecting above the top wall of the incubator chamber.

An open-ended pipe 23 is located within block 21 and its upper end terminates immediately below housing 22 while its lower end opens into said incubating chamber. 24 indicates a rod leading from a thermostat 24^a and its upper end has bearing in and projects through the bottom of housing 22. An 90

adjusting screw 25 has threaded engagement with plate 20^a and is in vertical alinement with thermostat rod 24. The lower end of screw 25 is provided with a seat in which is adapted to be seated the upper end of thermostat rod 24. In order to eliminate friction and insure the sensitive operation of the apparatus, the upper end of rod 24 is provided with a needle point and its seat in the lower end of screw 25 is preferably of conical shape. The lever 20 is a lever of the first order and its opposite or forward end is provided with a counterbalancing weight 26 which may be adjusted lengthwise of said lever and held in its adjusted position by 105 means of a set screw 26^a. 27 is a block likewise adjustably mounted on the forward end of lever 20, said block being held in its adjusted position by means of a set screw 28. Block 27 has an opening in its lower end 110 into which is inserted the shank of the hook 29, said shank being adjustable in vertical

plane in said block 27 and arranged to be locked in its adjusted position by means of a set screw 30.

31 is a ventilator closing plate or cap suspended by an eyed connection 32 from the hook 29. This ventilator cap coöperates with the top wall of the incubator and operates over a tubular extension 33 leading upwardly from a conical shaped or bell-mouthed ventilator escape 34. The lower edge of this ventilator escape is on a horizontal plane slightly below the plane of the hot water coil pipe which is located in the upper portion of the incubator chamber.

15 The purpose of this arrangement is to maintain a zone of heated fresh air at the top of the incubator chamber.

The thermostat 24^a is preferably located in the upper portion of the incubator chamber and approximately on a horizontal level with the lower end of the ventilator discharge opening so that it will be rendered more sensitive by the circulation of the air within the incubating chamber.

25 36 indicates air inlet openings in the bottom wall of the incubating chamber and preferably on each side of the water pans 37. 38 are the egg trays which are preferably formed with perforated or slatted bottom in a manner well known. These trays may be provided with turning devices, if desired, but such form no part of my present invention.

The operation of my improvement is extremely simple. Assuming that the eggs to be hatched are placed in the trays and the doors 39 in the front wall of the incubator units closed, a fire is built in the heater 2 (preferably, coal fire) and water having been poured into the tank 4, filling the system up to the desired level as indicated by the water gage 5. The thermometer 40, at the top of the water heating system in the heater 2 will indicate the temperature of the water in the heater system and also show the kind of fire to be maintained in the heater. To independently regulate the supply of hot water to the units in the battery and maintain the desired temperature 50 in the incubating chamber, each ball valve may be adjusted by turning screw 25.

In starting the operation of my improved incubator, the ball valve 17 is wide open and the ventilator 33 is closed by cap 31. As 55 the hot water circulates through the pipes in the incubator the temperature in said incubating chamber rises until it reaches the proper degree when the thermostat 24^a will operate rod 20 in its fulcrum, thereby partially closing ball valve 17 and partially opening ventilator 33 and said ball valve 17 and ventilator cap 31 will be maintained in this position as long as the temperature in the incubating chamber does not rise above 60 or fall below this predetermined degree.

During this time, lever 20 is in equilibrium, counterbalance 26 being adjusted on said lever so that it equalizes the pressure exerted by thermostat 24^a upon said lever, but any fall or rise of the temperature in said incubating chamber will decrease or increase the pressure exerted upon said lever 20 by thermostat 24^a, thereby overbalancing said lever and causing it to operate ball valve 17 and ventilator closure 31 accordingly.

When it is desired to change the degree at which the temperature in the incubating chamber is to be maintained, screw 25 is turned in the proper direction, thereby advancing or delaying the moment at which lever 20 will be overbalanced by thermostat 24^a, the counterbalance 26 being adjusted either toward or from the fulcrum of said lever in order to compensate for the difference of pressure exerted by said thermostat 24^a and thermostat rod 24 upon lever 20. In this manner, lever 20 is maintained in equilibrium when ball valve 17 and ventilator closure 31 are in the positions best adapted to maintain incubating chamber at the proper temperature and any fluctuations in the temperature of the incubating chamber will be readily responded to by thermostat 24^a and overbalancing lever 20 and actuating ball valve 17 and ventilator closure 31 to either raise or lower the temperature of said incubating chamber.

The ventilator cap may be horizontally adjusted to properly coöperate with the ventilator discharge opening and said cap may be likewise vertically adjusted with respect to the rod 20. The counterbalancing weight is finally adjusted with respect to the ball bearing fulcrum so that when the proper degree of temperature is exceeded in the incubating chamber, the ball valve will be lowered so as to close the supply of hot water to the chamber and simultaneously open the ventilator. When the chamber cools the ventilator is lowered and the ball valve 110 opened.

I claim:

1. In an incubator having an incubating chamber, the combination with a hot water heating system including a ball valve for controlling said system, of a ventilator for the incubating chamber, a ventilator closure member, a lever adjustably connected at one end to said ball valve and at its other end to said closure member, a housing supported on said incubator, a pivotal plate fixed to said rod and journaled on said housing, a tubular member extending downwardly from said housing into the incubating chamber, a thermostat positioned in the incubating chamber and having its operating rod extending upwardly through said tubular member into said housing, and means carried by said plate and operatively engaging said thermostat rod, said means being adjust- 130

able relative to said thermostat whereby the operation of said lever by the thermostat can be advanced or delayed by the adjustment of said means.

- 5 2. In an incubator having an incubating chamber, the combination with a hot water heating system for the incubating chamber, said system including a ball valve for controlling the admission of hot water to the 10 heating pipes in said incubating chamber, of an open ended tube forming the discharge opening for ventilating the incubating chamber, a ventilator closure for coöperating with said tube, a rod connected at one end to said ball valve and at the other end to said 15 ventilator closure, a plate fixed to said rod and pivotally mounted on said incubator to form a fulcrum for said rod, vertically adjustable means carried by said plate, and a 20 thermostat located in said incubating chamber and operatively engaging said adjustable means for overbalancing said rod, thereby opening the ball valve and closing the ventilator, or vice versa.
- 25 3. In an incubator provided with an incu-

bating chamber, a hot water heating system including a ball valve for controlling the circulation of hot water through the heating pipes in said incubating chamber, a ventilator pipe for the incubating chamber, a 30 ventilator closure, a lever of the first order connected at one end to said ball bearing and at the opposite end to said ventilator closure, a block supported on said incubator, a housing mounted on said block, a plate 35 fixed to said lever and pivotally mounted in said housing, vertically adjustable means carried by said plate, a thermostat mounted in said incubating chamber, and a rod connected to said thermostat and extending upwardly through said block into said housing to operatively engage said adjustable means carried by said plate whereby said lever is actuated by said thermostat, said means being adjustable to advance or delay the operation of said lever by said thermostat.

In testimony whereof, I hereunto affix my signature this eighth day of November, 1920.

JAMES S. BROWER.
